UNITED STATES PATENT OFFICE.

HUBERT C. ELLIS, OF CHICAGO, ILLINOIS, ASSIGNOR TO ELLIS DRIER & ELEVATOR COMPANY, OF CHICAGO, ILLINOIS, A CORPORATION OF WISCONSIN.

SULFUR-BURNER.

1,289,417.

Specification of Letters Patent. Patented Dec. 31. 1918.

Application filed August 18, 1915. Serial No. 46,382.

To all whom it may concern:

Be it known that I, HUBERT C. ELLIS, a resident of Chicago, in the county of Cook and State of Illinois, have invented certain new and useful Improvements in Sulfur-Burners, of which the following is a full, clear, and exact description.

The invention relates to sulfur burners.

One object of the invention is to provide an improved furnace adapted for the burning of a bleaching re-agent such as sulfur, for use in grain bleachers. Heretofore, difficulty has been experienced in the maintenance of sulfur burners, due to the extraordinary temperatures therein. In these furnaces it is particularly desirable to avoid any leakage of the fumes into the room in which the furnace is located. The invention is designed to provide a sulfur burner which is durable and which can be produced at a low cost and which is built so that the walls thereof will remain intact despite the high temperatures caused by the burning reagent.

The invention consists in the several novel features hereinafter set forth and more particularly defined by claim at the conclusion hereof.

In the drawings: Figure 1 is a vertical longitudinal section of a sulfur burner embodying the invention. Fig. 2 is a horizontal section taken on line 2—2 of Fig. 1. Fig. 3 is a vertical section taken on the line 3—3 of Fig. 1.

The improved furnace comprises a bed or base 10 formed of concrete and having suitable metallic reinforcement 11 therein. The combustion-chamber 12 for the sulfur is in an inner structure built of fire-brick and comprising a floor 14, a back wall 15, a front wall 16, a roof 17 and side walls 18. A horizontal baffle 19 extends backwardly from the front wall 16 and its rear end terminates some distance from the back wall 15 to leave a space for the passage of the sulfur fumes to the space above the baffle. The firebrick forming the baffle are supported by inverted T-bars supported in the side walls. The roof 17 is also sustained or built upon T-bars 21. A sleeve 22 forming the outlet for the fumes is built centrally in the top wall 17 to conduct the fumes to a pipe 22^a leading to the bleacher. Wall 16 is formed with an opening 23 through which the sulfur may

be placed onto the floor 14 and to admit air for combustion. 55

The furnace also comprises an outer structure supported upon bed 10, and separated from the inner structure containing the combustion chamber, at the sides, back, front and top, so as to form an insulating space 60 around the inner structure and so that the latter will be free to expand and contract responsively to the variation in temperature without distorting the outer structure.

In practice it has been found that by providing these disconnected or separated structures with an air space between them the furnace will be durable and danger of cracking and distortion of the walls will be avoided. 65

The outer structure comprises a front wall 24, a back-wall 25, side-walls 26, all formed of common brick, and a top wall 27 formed of concrete. The top-wall is formed of concrete with suitable metallic reinforcement 75 28 therein. The front wall 16 of the inner structure is extended around opening 23, as at 29, into the front wall 24 of the outer structure. Opening 23 extends through front wall 24 of the outer structure for the 80 admission of air. A door-frame 30 is fixed in the front wall 24 and a door 31 is hinged thereto, so that when the door is opened, sulfur may be readily shoveled onto the floor of the combustion-chamber. A rotatable register valve 32 is provided on the door 31 to admit air to the combustion-chamber in volume necessary for combustion. 85

Sleeve 22 is slidable in the opening 33 in the top wall 27 to form an expansion joint 90 between the fumes-conduit and the wall 27. Pipe 22^a leads from opening 33 to the bleacher and a packing 34 of asbestos is interposed between said pipe and the wall 27 to prevent the escape of fumes at the joint. 95 The ends of sleeve 22 and pipe 22^a are spaced apart to leave room for the sliding of the sleeve responsive to temperature variations.

In practice, it has been found that when a concrete top wall is employed, there is a tendency to sag at the center thereof, particularly in the absence of a central support for the wall. This sagging has a tendency to tilt the corners and marginal portions of the wall away from the side, front and top walls 100 of the outer structure. To overcome this,

tie-rods 35 anchored to the reinforcement 11 in the bed 10 are also anchored to the reinforcement 28 in the top wall 27, as shown in Fig. 1. These tie-rods are disposed at and adjacent each corner of the outer structure.

In operation, the sulfur placed on the floor 14 of the combustion chamber when ignited will produce fumes which will rise to or near the baffle, pass around the rear end thereof and thence between the baffle and the roof 17 to the outlet 22. Since the cold air enters at the register valve 32, and the fumes pass backwardly away from the front wall, the extension 29 of the inner structure will not be heated sufficiently to cause any substantial degree of expansion or contraction, so that this connection between the front walls of the inner and outer structures will not have any tendency to distort the front wall of the outer structure. It will be observed that all the walls of the inner structure, subjected to extremes of heat, are free to expand and contract responsively to the variations in temperature in the combustion chamber without exerting any distorting stresses upon the outer structure. At the fumes-outlet the expansion joint between the sleeve 22 and the top wall 27 permits expansion and contraction of the roof of the inner structure without exerting any distorting stresses upon the top-wall of the outer structure. The space formed between the inner and outer structures serves as an efficient insulation to prevent the heat in the combustion-chamber from passing through the outer structure into the room in which the furnace is located.

The invention thus exemplifies an improved sulfur burner which comprises inner and outer structures, with an insulating space therebetween, the inner structure containing

the combustion-chamber, and having its walls free to expand and contract without exerting any distorting stresses on the outer structure. Provision is made for rigidly securing and anchoring the concrete top of the outer structure to the concrete bed to prevent sagging of the said top. The furnace in its entirety is simple in construction, efficient in operation and can be produced at a low cost.

The invention is not to be understood as restricted to the details set forth, since these may be modified within the scope of the appended claim, without departing from the spirit and scope of the invention.

Having thus described my invention, what I claim as new, and desire to secure by Letters Patent, is:—

In a sulfur burner, the combination of a reinforced concrete bed, an inner structure built of fire brick and on the bed, having a combustion chamber with a closed floor therein and comprising surrounding walls and a roof of fire-brick, an outer structure built of brick and on the bed and having walls around and over the roof of the inner structure, the top wall of the outer structure being formed of reinforced concrete, tie-rods anchored in the bed and in said top wall, the inner and outer structures being spaced apart to form an insulating space therebetween and being disconnected to leave the inner structure free to expand without exerting distorting stresses on the outer structure, and an inlet and an outlet for the inner structure.

HUBERT C. ELLIS.
